UNITED STATES PATENT OFFICE.

HARRY S. HUMPHREYS, OF LANCASTER, PENNSYLVANIA, ASSIGNOR TO ARMSTRONG CORK COMPANY, OF PITTSBURGH, PENNSYLVANIA, A CORPORATION OF PENNSYLVANIA.

DESIGN FOR LINOLEUM, OILCLOTH, OR FLOOR COVERING.

60,681.

Specification for Design. Patented Mar. 21, 1922.

Application filed December 7, 1921. Serial No. 520,742. Term of patent 7 years.

To all whom it may concern:

Be it known that I, HARRY S. HUMPHREYS, a citizen of the United States, and a resident of Lancaster, in the county of Lancaster and State of Pennsylvania, have invented a new, original, and ornamental Design for Linoleum, Oilcloth, or Floor Covering, of which the following is a full, clear, and exact specification, reference being had to the accompanying drawing, forming part of this specification.

The figure is a plan view of a piece of linoleum embodying my design.

I claim:

The ornamental design for linoleum, oilcloth, or floor covering as shown.

HARRY S. HUMPHREYS.
